SUPPORTING GRILLE-BLADES FROM
RADIATOR SHELLSLee B. Green, Lakewood, Ohio, assignor to The
Globe Machine & Stamping Company, Cleve-
land, Ohio, a corporation of Ohio

Application October 20, 1934, Serial No. 749,248

8 Claims. (Cl. 293—54)

My invention relates to metal grilles (or guards) of the class in which generally parallel grille blades (or guard bars) are fastened at their ends respectively to two end members; and 5 in its general objects aims to provide both a novel arrangement for anchoring the blades to the end members, and novel means for fastening these end members to the apertured member which has its aperture guarded by the grille.

10 When a parallel-bladed grille is used for guarding the air-admitting opening in the so-called radiator shell of a modern passenger automobile, this grill usually includes substantially upright blades spanning two generally horizontal end members. These end members are desirably fastened to the rearward or inner face of the front member of the radiator shell, respectively above and below the aperture across which the grille blades extend, so that the end members will be 15 concealed.

In the earlier practice, such end members of a grille were sometimes fastened to the so-called radiator shell front by bolts each extending both through the said front and through one of the 20 end members. But such a bolt arrangement has the serious objection that it requires the lateral spacing of the bolt-receiving perforations in each end member to correspond exactly with that of perforations in the radiator shell front, and 25 likewise requires the vertical spacing of the apertures in the two end members to correspond exactly with the spacing between corresponding perforations in the upper and lower portions of the radiator shell front; thereby demanding 30 a greater exactness in the boring of the said shell front and more particularly in the manufacture of the grille than is consistent with the economical production of such a grille. Moreover, any bolt heads or nuts exposed on the front 35 of the radiator shell detract from the ornamental design of such a frontal automobile part.

Furthermore, many types of end members heretofore used in parallel-bladed grilles do not lend themselves readily to the providing of suitably positioned bolt-receiving apertures, unless 40 such end members are modified by attaching auxiliary flanges or brackets at a considerable additional cost. So also, the quite extensively used bead (or forwardly convexed moulding) formation around the aperture in a radiator shell front would not afford the flat bearing for bolt-heads 45 which usually is essential for firmness.

In one of its major objects, my invention aims 50 to provide a simple, light and inexpensive end member for a grille, designed so as to bear direct-

ly against the inner face of a radiator shell front (or other apertured grille-supporting member) and presenting a ledge in convenient position for engagement by hook elements on the said shell front. To cooperate with such hook-engaging ledges on the end members of the grille, my invention also aims to provide a radiator shell front having the portions adjacent to the blade-spanned aperture formed so as to present integral hook fingers which can readily be bent 10 into engagement with such ledges on the end members of a grille, and also formed so that these hook fingers can anchor the grille firmly to the shell front while still permitting this shell front to present a frontal bead surrounding the 15 said aperture. Furthermore, my invention aims to arrange the just recited hook finger provision so as to allow for manufacturing variations in the dimensions of the grille, and so as to facilitate the attaching of the grille to the radiator 20 shell front.

In another major object, my invention aims to provide a novel and inexpensive arrangement for anchoring generally flat grille blades to end members. For this purpose my invention aims to 25 provide both a novel blade-end construction and corresponding formations on the end members of the grille, and also aims to dispose these features of the end members so that they will effectively cooperate with the previously recited fastening of the end members to the radiator shell for positioning the grille so that both its end members and the juncture of the grille blade portions with these end members will be concealed by the radiator shell front.

Illustrative of the manner in which I accomplish the above recited objects, Fig. 1 is a fragmentary vertical section through a grille and radiator shell front combination embodying all features of my invention, taken along the line 30 1—1 of Fig. 5.

Fig. 2 is a fragmentary perspective view of the upper end member of the grille and of the adjacent portion of the radiator shell front, taken 35 from the rear and with a blade omitted to show the corresponding perforation in the end member.

Fig. 3 is an enlarged and fragmentary rear elevation of the part of the radiator shell front adjacent to the top of the aperture in the said shell front, showing the hook finger elements as initially formed.

Fig. 4 is a perspective view of the upper end portion of one of the blades, taken before the blade was attached to an end member.

Fig. 5 is a fragmentary front elevation of the grille alone.

Fig. 6 is a fragmentary plan view of the upper end member.

- 5 Fig. 7 is a fragmentary vertical section, allied to the upper part of Fig. 1, showing the end member as also including a stiffening flange at its rear, and showing the shell front as not ornamented by a frontal bead.
- 10 Fig. 8 is a vertical section through the upper portion of a grille, showing a simplified shaping of the end member when not intended for attachment to its support after the manner of Fig. 1.

- 15 Fig. 9 is a perspective view of an upper portion of an entirely flat blade also suitable for attachment to an end member according to my invention.

In Figs. 1, 2 and 5, the grille includes a plurality of coparallel and approximately upright blades spanning two end members which are of counterpart but relatively inverted cross-section. Each blade consists of a strip 1 of sheet metal of suitable length which has one longitudinal edge portion curled into a tube. This curled portion T (which is to be at the front in the grille) terminates short of each of the still flat portion 1 of the strip, so as to leave a flat rearward tab 2 projecting at each end of the blade beyond the

30 said curled portion.

Then I provide two end members, the upper of which includes an approximately horizontal web W provided with parallel rectangular slots S, each corresponding in section to one of the said tabs 2. This upper end member also has a riser web 3 extending upwards from the forward edge of the flat web W, and a hook-engageable web 4 extending rearwardly from the upper edge of the said riser web, this web 4 being desirably 40 of considerably less width than the slotted web W.

When the upper edge 5 of the aperture in the radiator shell front is not a straight line, both of webs W and 4 are preferably bent correspondingly, as shown for example in Fig. 2.

To fasten the upper end member to the blades, each blade has its upper tab portion 2 slid upwards through one of the slots S in the upper end member until the upper end of the tubular frontal portion T of the blade engages the bottom of the slotted web W. The part 2a of this tab portion which projects beyond the web W is then bent forcibly down against the said web. This clamping of the said web against the said upper tube end then cooperates with the interfitting of the slot S by the tab portion within that slot to fasten the blade rigidly to the upper end member. Indeed, I have found in practice that a forcible bending of the tab portions 2a against the slotted web W will effect a firm clamping of the blades to this web even when the slot-housed portions of the tabs do not tightly fit the bores of the slots.

The lower ends of the blades are similarly fastened to the lower end member, which may be generally an inverted counterpart of the above described upper member, except for the shaping of its generally horizontal webs W' and 4a to correspond to the contour of the lower edge of the aperture spanned by the grille blades. Thus, Figs. 1 and 5 show both the wider web W' and the narrower (hook-engageable) web 4a as bent flatwise to correspond to the shape (indicated by the lower dotted line 5 in Fig. 5) of the adjacent lower part of the aperture edge in the

radiator shell. In practice, the blades of the grille preferably also have their flat portions connected and rigidly spaced by cross-members, such as the tie-bars 8 of Figs. 1 and 5, these being shown as of the type more fully disclosed in my copending application #734,611, filed July 11, 1934 on a Grid-type radiator grille.

For use with the just described grille, I form the radiator shell front 9 so as to include an interior flange 10 extending radially outward from the said aperture in the shell and bearing forward flatwise against the frontal portion 11 which borders that aperture. This interior flange preferably extends entirely around the said aperture, so as to stiffen the shell front and so that the recurring of the metal during the forming of this flange affords an aperture edge of rounded section, as shown in Figs. 1 and 2. However, for my here presented purpose, I only require such flanges along the top and bottom of the said aperture. I also preferably make each of these top and bottom flange portions 10 of a somewhat greater width than the riser webs (3 and 3a) of the end members, and make the blades of such a length that the slotted webs of the two end members will be spaced more widely (opposite each blade) than the height of the adjacent portion of the frontal aperture in the radiator shell.

Each of the said interior flanges 10 has a plurality of laterally spaced extension fingers F extending from the free edge of the flange, namely upwardly from the upper flange and downwardly from the lower flange, each such finger being of greater height than the width of the narrower web (4 or 4a) of one of the end members, each of which fingers later on is bent into hooking engagement with the narrower web (4 or 4a) of one of the end members.

To facilitate the attaching of the grille to the thus constructed radiator shell front, the extensions or fingers F on the lower interior flange may first be bent rearwards at right angles to the inner face of that flange, as shown in dotted lines at Fa in Fig. 1, thereby affording ledges upon which the narrower web 4a of the lower end member can be seated to sustain the weight of the grille while the rearward portions Fb of these fingers are bent (as shown in full lines in Fig. 1) to bear against the said narrower web 4a and while the tip portions Fc of each such finger is bent downwards against the said narrower web.

The extension fingers 12 on the upper interior flange 10 may initially extend upwards, as shown in dotted lines at F' in Fig. 1, and after the lower end member has been anchored to the shell front in the just described manner, these upper extension fingers are bent down against the narrow web 4 of the upper end member and the tip portion of each of these fingers is bent forwardly under the said web and into upward engagement with that web, as shown in full lines in Fig. 1.

During each of these finger-bending operations, the location of the bends is determined by the position of parts of the adjacent end member, so that my grille-anchoring provisions automatically compensate for manufacturing variations in the dimensions of the end member and in the clear spacing between the two end members. Moreover, since the narrower webs 4 and 4a of the two end members can be of relatively small width, I have found that the thickness of metal commonly used for radiator shells af-

fords ample strength for rigidly supporting a thus attached grille.

In practice, I preferably make the interior flange 10 on the radiator shell wider than the 5 riser web (3 or 3a) of the end members, and make each blade of greater length than the spacing of the upper and lower edge portions of the frontal shell aperture spanned by that blade, so that radiator shell front conceals the end 10 portions of the tubular parts T of the blades. Then, if the car manufacturer wants the radiator shell front to present a forwardly convexed bead around the edge of the shell aperture, this can readily be afforded by attaching a separately formed moulding M having recurved flanges bearing against the flat-sectioned shell front 15 part 11 which is in front of the interior flange 10.

In manufacturing my here presented grille, blades of suitable length can first be rigidly cross-connected by tie-bars 8, as in Figs. 1 and 5, and each end member may consist of a strip of steel formed to the needed unequal-angled channel section and having its wider channel web provided with the suitably spaced slots S. The upper tabs 2 (Fig. 4) of all blades can then be slid simultaneously through the slots in the wider web W of the upper end member, after which the projecting portions of all of these tabs can be clinched against that web by a single punch- 20 press operation. The other ends of the blades can then similarly be speedily fastened to the lower end member, so that the entire assembly 25 of the grille is both expeditious and low in cost.

Moreover, when each slot S in an end member corresponds substantially in its bore section 30 to that of a blade tab 2, this interfitting of the slots and tabs cooperates with the tie-bars 8 to prevent all relative movement of the blades. Consequently, I can firmly anchor the blades to 35 the end bars even when the inward faces of the slotted web (W or W¹) are curved as in Fig. 5 so that these faces will engage only part of the adjacent end of the tubular part of each blade. So also, the simplicity of my provisions for anchoring the end members to the radiator shell 40 will be obvious; and it will be noted that neither these anchoring provisions nor the assembling of the grille include any auxiliary fastening elements, or requires any welding or brazing operations.

However, while I have heretofore described the end members of a grille as including a rearwardly extending web having slots through which 45 endwardly projecting tab portions of blades can be clinched, and also including a second rearwardly extending web disposed for engagement with hook fingers on a radiator shell front, I do not wish to be limited to the conjoint use of these or other features of my invention.

So also, it should be obvious that many changes from the heretofore described embodiment might be made without departing either from the spirit 50 of my invention or from the appended claims, and that both my grille-blade and end-bar assembly 55 and of my hookingly supporting such as assembly would also be advantageous in connection with other grille-supporting members than a radiator shell.

For example, if my grille is to guard an air-admitting aperture in a side wall of an air-conditioning unit, each end member might be of the simple angle-iron section shown in Fig. 6, in which this member merely comprises a slotted web W (as in Fig. 2 or 6) and a stiffening web 14 depending from the rear edge of the web W. On the

other hand, the end member of Figs. 1 and 2 may be provided with an auxiliary stiffening web 4c as shown in Fig. 7.

So also, the cross-sectional shape of the blades may be varied, so long as the end tabs of these blades substantially fit the slots through which they are clinched. Thus, Fig. 9 shows the upper end portion of an entirely flat blade 15 which has no ornamental tubular frontal portion, and which would serve for a frontal grille on automobile trucks.

I claim as my invention:

1. The combination with a substantially upright supporting member having an aperture, of a grille comprising two rearwardly open channel-sectioned end members disposed behind the supporting member and extending respectively adjacent to two opposite sides of the aperture, and grille elements spanning the aperture and fastened at each end to the channel web of the adjacent end member which is nearest to the said aperture; each end member having its channel-back bearing forwardly against the supporting member; the supporting member having two rows of fingers extending rearwardly from it respectively adjacent to the other channel-web of one of the end members, and each of the said fingers having its tip portion hooked over the free edge of the channel-web adjacent to it.

2. A supporting member and grille combination 30 as per claim 1, in which each of the said fingers bears flatwise against the outer face of the channel-web over the free edge of which the tip portion of that finger is hooked.

3. A supporting member and grille combination 35 as per claim 1, in which the two end members have alined perforations in the channel webs thereof which are nearest to the said aperture, and in which the grille elements are blades; each blade extending through a pair of alined perforations in the two end members.

4. A supporting member and grille combination 40 as per claim 1, in which the two end members have alined perforations in the channel webs thereof which are nearest to the said aperture, 45 and in which each end of a blade has two longitudinally spaced portions thereof respectively engaging the two sides of the perforated channel web of the end member which is adjacent to that blade end.

5. A supporting member and grille combination 50 as per claim 1, in which the two end members have alined perforations in the channel webs thereof which are nearest to the said aperture, 55 and in which the grille elements are blades; each end part of a blade comprising a forward portion abutting endwise against the perforated channel web of the end member adjacent to that blade end part, and a rearward portion extending through a perforation of the same channel web 60 and having its tip bent into engagement with the inner face of the said same channel web.

6. In combination, a sheet metal supporting member provided with an aperture, the parts of the said member adjacent to opposite ends of the 65 said aperture being recurved rearwardly to constitute two flanges each extending radially outward of the said aperture behind an adjacent frontal portion of the supporting member, the supporting member including spaced fingers projecting rearwardly from the free edge of each flange; two rearwardly open channel-sectioned 70 end members each extending longitudinally of one of the said aperture ends and each having its channel-back bearing forwardly against one 75

of the said flanges, the fingers projecting from each of the said flanges being hooked over the free edge of that channel-web of the end member adjacent to the said flange which is farthest 5 from the aperture; and guard elements spanning and secured to the other two channel-webs of the end members.

7. A combination of a supporting member, end members and guard elements as per claim 6, in 10 which each of the said fingers bears against the outward face of the channel-web of the adjacent end member which is farthest from the aperture in the supporting member; and in which the channel-back of each end member is of less width 15 than the recurved flange of the supporting member against which that channel-back bears; whereby the supporting of the end members by the said fingers spaces each end member radially of the aperture from the aperture end adjacent 20 to that end member.

8. A grille comprising spaced and generally flat blades presenting their flat faces substantially parallel to each other and presenting their forward edges in a common frontal surface, each blade end part having its rearward portion longer than its forward portion; and two end members each including a web extending approximately at right angles to the said frontal surface and wider than the blades; the said webs of the two end members having aligned perforations spaced rearwardly from the forward edges of the said webs, through which perforations the longer end parts of the blades are clinched, and each blade having the forward and shorter portion of each end part of the blade abutting along substantially the entire width of this end part against a portion of the adjacent end member which is forward of the 15 perforations in that end member.

LEE B. GREEN. 20
